PAUL WRIGHT, OF BIRMINGHAM, ALABAMA.

CAST-IRON-COLUMN CONSTRUCTION.

1,264,245.

Specification of Letters Patent. Patented Apr. 30, 1918.

Application filed April 12, 1917. Serial No. 161,503.

To all whom it may concern:

Be it known that I, PAUL WRIGHT, a citizen of the United States, residing at Birmingham, in the county of Jefferson 5 and State of Alabama, have invented a new and useful Cast-Iron-Column Construction, of which the following is a specification.

This invention has reference to cast iron column construction, and its object is to 10 provide a construction for use in connection with concrete beams, framing and floors, whereby the iron columns replace concrete columns, and thereby save valuable space and provide less light obstruction than is the 15 case with concrete columns of the same carrying capacity.

In accordance with the invention the columns comprise superposed sections with separately formed caps surmounting a lower column section and receiving the next higher column section with the cap sustaining the beam load without breaking the continuity of the column sections, and at the same time centering the sections.

25 The structure is such that the columns may be filled with concrete from end to end with the concrete reinforced at the splices, thereby producing a rigid connection capable of resisting a tendency to lift.

30 The cap constituting the splice may be of such construction as to support one or more beams, which latter may or may not be continuous over the support. Thus the economies of all-concrete constructions, that is 35 column and beam constructions, are obtained.

The invention will be best understood from a consideration of the following detailed description, taken in connection with 40 the accompanying drawings forming part of this specification, with the further understanding that while the drawings show a practical form of the invention, the latter is not confined to any strict conformity with 45 the showing of the drawings, but may be changed and modified so long as such changes and modifications come within the scope of the appended claims.

In the drawings:—

50 Figure 1 is an elevation of an iron column and concrete beam construction embodying the invention.

Fig. 2 is a section through the column in a direction at right angles to the column as 55 viewed in Fig. 1.

Fig. 3 is a plan view of the cap.

Referring to the drawings, there is shown a column section 1, which may be of cast iron, and another column section 2, which may also be of cast iron, and which 60 is superposed on the section 1. The columns are both of tubular construction and are of materially less diameter than concrete columns of the same carrying capacity. Where space is valuable the smaller diameter 65 of the columns is decidedly advantageous. Moreover, such iron columns are less obstructive to light than is the case with concrete columns of like carrying capacity.

Applied to the upper end of the lower 70 column, considering the latter as upright, is a cap 3, having a floor 4 extended in one direction. On opposite long sides of the floor 4 are correspondingly extended upstanding flanges 5, and rising intermediately of the 75 length of the floor 4 is an upstanding thimble 6 about an opening 7 through the cap, the sleeve 6 being suitably spaced from the flanges 5.

Depending from the floor 4 is an annular 80 sleeve 8 concentric with the opening 7 and of greater internal diameter than the external diameter of the thimble 6 in the particular showing of the drawings.

The upper end of the column 1 is machined 85 so as to snugly fit into the sleeve 8 with a sufficient degree of accuracy where the metal surfaces are in contact to insure substantially true alinement and good bearing. The column section 2 is also machined 90 at the end surrounding and receiving the thimble 6 and where resting on the floor 4 immediately about the thimble 6 so as to insure substantially true alinement and good bearing. This brings all the contacting 95 metal surfaces into direct load transmitting relation without reduction of section or internal diameter. Moreover, the cap splice for the columns transmits the beam loads 100 without breaking the continuity of the columns, and at the same time centers the upper and lower sections.

The cap is applied to the lower column section and the column is filled with concrete and reinforcing rods 9 are introduced 105 into the lower column section through the passage 7 in the cap, with the upper ends of the reinforcing rods rising above the top of the cap. The upper column section 2 is then applied to the cap, automatically centering thereon with the reinforcing rods 9 110 entering the lower end of the upper column

section, and said section is then filled with concrete, whereby the column made up of two or more sections has a continuous core of concrete filling it. The concrete serves to reinforce and stiffen the column, and the concrete and reinforcing strips at the joint or splice provide a rigid connection capable of resisting all lifting tendencies, it being understood, of course, that the column is fixed or anchored at its lower end, as is customary.

The floor 4 supports concrete beams 10 which may be formed in the ordinary manner with reinforcing strips 11, but these features do not in themselves enter into the present invention. The cap 3 may support one or more beams which may or may not be continuous over the support. The construction, however, is such that all the benefits of an all-concrete beam and column arrangement are obtained while certain disadvantages are eliminated, among which disadvantages are the massiveness of concrete columns as compared with cast iron columns of the same carrying capacity and the smaller obstruction to light found in iron columns, because of their materially smaller diameter for the same carrying capacity.

The column cap has an outside sleeve fitting snugly over the upper end of the lower column section and a thimble fitting snugly into the lower end of the upper column section, and thus holding the two column sections in perfect alinement, while the outside elongated flanges 5 support the beam load and may be arranged to support either one beam or a plurality of beams.

The cap with the flooring or bracket con-

stituting a support for the beams provides for the transmission of the column loads without reduction of column section where passing through the floor. Moreover, the combined cap and bracket makes possible the use of plain columns where otherwise it has been found necessary to provide expensive columns with brackets cast on them.

What is claimed is:—

1. Metal and concrete column construction, comprising tubular metal sections, a metal splicing cap between them, concrete filling for and uniting the columns, and concrete beams on the cap integrally joined about the column section above the cap.

2. Metal and concrete column construction, comprising tubular metal sections, a metal splicing cap between them having a portion fitting snugly into the upper column and spaced exteriorly therefrom, with the lower column fitting snugly into the cap, concrete filling for and uniting the columns, and concrete beams on the cap integrally joined about the column section above the cap and filling the space between the cap and the upper column section.

3. Metal and concrete column construction, comprising superposed tubular metal sections with a continuous interior concrete filling and beams integrally joined about and in contact with the column sections at their junction.

In testimony, that I claim the foregoing as my own, I have hereto affixed my signature in the presence of two witnesses.

PAUL WRIGHT.
